UNITED STATES PATENT OFFICE.

OTTO BUNSE, OF HESPERINGHAUSEN, NEAR NIEDERMARSBERG, GERMANY, ASSIGNOR
TO FRITZ BUNSE, OF BRAUNSCHWEIG, GERMANY.

SEED SELECTING AND CLEANING MACHINE.

Application filed April 20, 1923, Serial No. 633,543, and in Germany March 7, 1923.

My invention relates to an improved machine or so-called "tricuer" for cleaning seeds by selecting and separating therefrom foreign bodies or particles, particularly 5 weed-seeds.

Generally speaking, machines of the kind, as hitherto employed, mainly comprise a rotary drum having small pockets in its inner peripheral surface for picking up and lifting seed-grains of smaller size (weed-seeds) from a charge of seed supplied to the drum in order to be freed from weed-seeds, and which constantly remains in the bottom part 10 of the rotating drum, whilst the weed-seeds are lifted up by the said pockets and dropped into a stationary collecting trough or similar vessel provided within the drum over the whole of the length thereof.

The said pockets are of a size to allow the 20 weed-seed grains to snugly fit and remain therein for approximately the whole of the ascending movement of the pockets, but to not allow the useful seed grains which are of a larger size, to embed therein. If, however, 25 the useful seed grains are so shaped or sized as to be yet received by the pocket once in a while, the thus captured seed-grains will project therefrom and soon drop back into the charge without ever ascending 30 so far as to drop into the above mentioned trough.

The efficiency of a machine of the stated 35 type obviously depends upon its running speed. In the machines as hitherto constructed or suggested the rotary speed is limited by the charge being imparted an up and down going or fluctuating movement as soon as a certain velocity is reached. This fluctuation of the charge within the rotating 40 drum exercises an unfavourable influence on the selecting operation for the following reasons:

At any excessive speed the centrifugal 45 force acts to press the charge firmly towards the inner face of the drum so as to cause the former to stick thereto and to run therewith instead of uninterruptedly falling back as at a low speed. In consequence thereof the pockets fail to work until the circumferential speed is reduced, say to at least 0.4 m. per second only. At this speed the selected 50 weed-seed grains already drop out of the pockets when they reach the horizontal cen-

tral plane of the drum, that is to say, at a level where it is very difficult to gather them 55 for separation from the useful seed grains.

The object of my invention is to provide means by which the efficiency of the machine will be greatly enhanced owing to the fact that the selecting drum can be given a 60 running speed highly in excess of the peripheral velocity possible in machines of the class hitherto devised, e. g., a drum of a diameter of 600 mm. may be given a peripheral velocity of about 1.6 m. per second. 65 To this end I provide, according to my invention, retaining, braking or stopping members in the drum mounted longitudinally therein and acting to prevent the charge from going up and down or fluctuating, 70 so that higher speeds can be utilized without reducing the selecting action of the pockets. These members, for instance flat iron rails, or bars or rollers, retain the charge or seed mass so that it slides upon the inner 75 pocket surface of the drum.

Having thus set forth in general the principle upon which my invention depends and having pointed to the particular improvements and advantages effected over the prior 80 art I shall now particularly describe one simple embodiment thereof which I have shown in the accompanying drawings for the purpose of more fully disclosing my invention; but it is to be understood that the 85 drawings illustrate only one of the numerous possible embodiments of my invention, and that I do not limit myself thereto inasmuch as many modifications may be devised by those skilled in the art without departing 90 from the spirit of my invention.

In the drawings—

Figure 1 is a sectional view of the machine embodying my invention, taken on the line 1—1 of

Figure 2, which is a longitudinal section, the left hand portion of which being taken on the line 2—2 and the right hand portion taken on the line 3—3 of Figure 1;

Figure 3 is a plan view of a part of the 100 machine;

Figure 4 is a perspective view of the retaining or braking members;

Figure 5 shows one of the supporting 105 bearings of the drum,

Figure 6 is a cross-sectional view of a

portion of the wall of the drum with a retaining member and

Figure 7 illustrates the arrangements of the pockets on the inner side of a portion of the wall of the drum.

The inner face of the cylindrical wall of the open-ended drum 1 is provided with the usual pockets 2, as shown in Figures 6 and 7. Mounted on the two ends of the drum are rings 4 and 5 made of cast-iron and interconnected by means of bolts or rods 3 and nuts. The ring 4 is shaped to form a running tread 6 of wedge-shape and the ring 5 is shown to have a similar running tread 7 of cylindrical circumference. The tread 6 is supported by wheels 8 having a peripheral groove 8² of corresponding wedge-shaped cross-section for the tread to engage therein so that the drum will be prevented from axial displacement. The supporting wheels 9 of the tread 7 are of cylindrical shape to conform to the tread but it goes without saying that both the tread 7 and the wheels 9 may also be given a wedge-shaped or angular cross-section, if desired.

The lower wheels 8 and 9 are keyed to a longitudinally extending shaft 8¹ duly supported at its ends in bearings carried by the cross-beams 10 and 11, whilst the upper wheels 8 and 9 are keyed to a similar shaft 12 supported in bearings carried by the vertical beam 11¹. Keyed to the shaft 12 is a pulley 13 for a belt to be driven by any suitable power engine not shown, so that the upper wheels 8 and 9 are the driving members of the drum, whereas the lower wheels 8 and 9 are mere supporting and guiding members.

The drum is supplied with a charge of seed, preferably continuously, at the one end where a feeding funnel 14 is provided for the purpose as indicated by dotted lines in Figure 2. The ring 5 is cast integral with a wide annular flange 5¹ extending in the vertical end plane of the drum for the purpose of preventing the fed in seed from falling out at this end of the drum.

In the lower portion of the drum 1 a screw-conveyor 15 is provided. Said conveyor extends through the whole of the length of the drum with its shaft projecting through the open ends of the latter so as to be supported in suitable bearings carried by the two cross-beams 16 and 17 of the machine frame. The conveyor 15 acts to slowly move the charge or seed from the one end of the drum where the feeding funnel 14 continuously replenishes, towards the other end, where an outlet-funnel 18 is provided to receive the purified seed. On the way from the feeding funnel 14 to the discharge-funnel 18 the seed is subjected to the selecting action of the pockets 2 which uninterruptedly pick out the weed-seed grains (of smaller size) owing to the contin-

uous rotation of the drum, as will be readily understood on inspection of Figures 6 and 7.

The picked-out grains are taken along by the drum up to a certain height or point where they fall out of the pockets into a stationary trough 19. A screw-conveyor 20 is provided in the latter for the purpose of driving the selected weed-seed grains towards an outlet-pipe 21 connected with the trough at the delivery end of the drum and acting to forward the grains into a collecting vessel or the like. The two screw-conveyors 15 and 20 are driven by the main shaft 12 through the agency of pulleys 12¹, 12², 15¹, 20¹ and belts 30 and 31 respectively.

According to my invention longitudinal bars, boards or plates, made of suitable material such as sheet-iron or the like, are inserted in the drum at a place near the ascending side of and preferably parallel to the wall of the rotating drum, as will be readily understood from Figure 1. In the embodiment shown four such plates 21¹, 22, 23 and 24 are provided, but I wish to have it understood that the number of plates is not essential, it being obvious to those versed in the art that more or less boards or plates or rails may be provided to ensure the desired effect, just in accordance with the particular construction of the machine and the kind of seeds to be treated. Further I desire to emphasize that the boards or plates 21¹, 22, 23, 24 may constitute or represent any desired or suitable form and that all or any of the stated constructional elements may be given a cross-sectional shape of any desired or suitable contour. Furthermore I wish to point to the modifications within the scope of my invention according to which the retaining, braking or stopping members may comprise, instead of simple and immovable plates, boards or bars and other suitably arranged and formed elements capable of preventing the charge from rising with the drum.

The retaining plates 21¹, 22, 23 and 24 in the embodiment shown extend within the drum over the whole of the length of the latter and are connected and supported at their ends by two vertical members 25 and 26 with which they form a structure in the shape of a grate, that can be inserted into the drum as a whole, as will be readily understood from Figure 4 showing one end portion of the said structure. The said vertical members or plates 25, 26 are equipped with flanges or laps 28 bent off at right angles to afford a means for the connection with an angle-bar 27 extending longitudinally and parallel to the retaining plates in the drum. The said laps 28 are riveted or detachably connected with the bar 27 firmly attached to the cross-beams 16 and 17 of the frame of the machine. As illustrated in the drawings the collecting trough 19 is sup-

ported at its two ends by the uppermost cross-beams of the frame, but the vertical end-plates 25, 26 may be shaped and disposed to serve as a means for supporting the 5 said trough 19, if required or desired.

The horizontally arranged plates 21¹, 22, 10 23 and 24 act to retain the ascending seed in a manner that the lowermost layer of seed grains immediately in touch with the wall of the rotating drum will be constantly kept 15 in a sliding movement with relation to the drum wall. In this way a proper selecting operation will be ensured, since the smaller seed grains (weed-seed) thus get more readily access to the pockets and the larger seed grains (useful seed) incidentally received by the pockets and projecting therefrom owing to their larger size, are tilted and thrown out again off the pockets by the 20 charge or layer of seed constantly moving in opposition, that is to say, in a direction opposed to the rotary movement of the drum, so that the pockets will be accessible again to the smaller weed-seed grains which snugly 25 fit therein so as to be taken along up to the point of dropping into the trough 19.

The uppermost retaining plate 21¹ is bent down at an angle to form a guiding face 21² for the seed grains that have been elevated 30 above and over the plate 21¹ properly speaking, that is the inclined and upwards extending portion thereof. The said guiding face 21² acts to return the elevated seed grains to the bottom of the drum as will be 35 clearly seen on inspection of Figure 1. In this manner the seed grains will be properly stirred and mixed and turned over and over again, so that the charge fed into the drum will, on its way from the inlet 14 to the 40 outlet 18, bring all of its layers or strata into immediate contact with the wall of the drum, whereby all of the weed-seed grains are caught by the pockets 2 and carried off into the collecting trough 19 at a comparatively 45 high running speed of the drum. Obviously the lower plates 22, 23 and 24 likewise act to turn over and return the seed to the bottom of the drum by causing the elevated grains to fall off over the inner marginal 50 edges of the plates.

It is to be noted that the known screw-conveyor 15 usually located within the drum at the lowest part thereof cannot act and is not intended to act as a retaining and 55 returning member, for the reason that the seed does not accumulate in the vicinity of the said conveyor and the latter cannot cause the seed to slide on the essentially horizontal portion or bottom of the inner face of the drum, nor even contribute to impart to the seed or charge a sliding movement as hereinbefore explained with respect to the described retaining or braking members.

From the foregoing description it will be 60 seen that simple and efficient means are here-

in provided for accomplishing the objects of my invention, but while the elements shown and described are well adapted to serve the purposes for which they are intended, it will be understood that the invention is not limited to the precise construction set forth, but includes within its purview such changes as may be made within the scope of the appended claims.

What I claim is:

1. A seed selecting and cleaning machine, comprising a drum, pockets on the inner face of the wall of the drum, means for imparting rotary motion to the drum, a conveyor within the drum, and means lying 70 within the charge to be selected and retaining the charge so that the whole charge slides upon the inner pocketed surface of the drum and strikes off the projecting grains from the pockets, and permits of the immediate 75 filling of the pockets with small undesirable grains.

2. A seed selecting and cleaning machine, comprising a drum, pockets on the inner face 80 of the wall of the drum, means for imparting rotary motion to the drum, a conveyor within the drum, means for actuating said conveyor, and a stationary retaining and returning plate located in the drum and extending longitudinally therein in the vicinity of and parallel to the ascending side of the wall of the said drum, essentially as and for the purpose set forth.

3. A seed selecting and cleaning machine, comprising a drum, pockets on the inner face 90 of the wall of the drum, means for imparting rotary motion to the drum, a conveyor within the drum, means for actuating said conveyor, and a stationary retaining and returning structure composed of a plurality of 95 bars arranged below one another in the peripheral direction of the drum longitudinally disposed in the drum near and parallel to the ascending side of the wall thereof, essentially as and for the purpose set forth.

4. A seed selecting and cleaning machine, comprising a drum, pockets on the inner surface of the wall of said drum, means for imparting rotary motion to the drum, a conveyor within the drum, means for actuating 100 said conveyor, and a stationary withholding and returning member composed of stationary side members and a series of bars of suitable profile rigidly connected between 105 said side members to form a grate-like 110 structure, essentially as and for the purpose set forth.

5. A seed selecting and cleaning machine, comprising a drum, pockets on the inner face of the wall of the drum, means for imparting rotary motion to the drum, a conveyor within the drum, means for actuating said conveyor, and stationary means for retaining and returning to the bottom of the drum those parts of the seed or charge tend- 115 120 125 130

ing to be taken along by the wall of the drum through the action of centrifugal force, substantially as described.

6. A seed selecting and cleaning machine, comprising a drum, pockets on the inner face of the wall of said drum, means for imparting rotary motion to the drum, a conveyor within the drum, means for actuating said conveyor, and stationary members having parts for retaining and returning to the bottom of the drum those parts of the feed or charge tending to be taken along by the wall of the drum through the action of centrifugal force, substantially as described.

15 7. A seed selecting and cleaning machine, comprising a support, a drum rotatably mounted therein, pockets on the inner face of the wall of said drum, a stationary trough located in the top of the drum beneath the inner face of the wall thereof, a conveyor operating in said trough, a feed conveyor operably mounted in the lower part of the

drum, means for actuating said conveyors and means for retaining and returning to the bottom of the drum those parts of the feed tending to be taken along by the wall of the drum through the action of centrifugal force including stationary guide members connected with the support and a plurality of longitudinally disposed bars arranged behind one another in the peripheral connection of the drum and connected between said side members forming a grate-like structure, substantially as and for the purposes set forth.

8. In an arrangement as claimed in claim 7, wherein a guide continues at an inclination from the upper bar and acts as a return for elevated seed grains to the bottom of the drum.

In testimony whereof I have affixed my signature.

OTTO BUNSE.
